Primary Examiner—Alan P. Douglas*Assistant Examiner*—Robert M. Spear*Attorney, Agent, or Firm*—Finnegan, Henderson, Farabow, Garrett & Dunner[57] **CLAIM**

The ornamental design for an embossed facial tissue sheet, as shown and described.

DESCRIPTION

FIG. 1 is a top plan view of an embossed facial tissue sheet embodying my design.

The broken line boundaries of FIG. 1 indicate that the design may continue in one or more directions, and are for illustrative purposes only, forming no part of the claimed design.

FIG. 1
